MORGAN L. FITCH, OF COOLEDGE, TEXAS.

STOVEPIPE-ANCHOR FOR TENTS.

1,245,895.

Specification of Letters Patent.

Patented Nov. 6, 1917.

Application filed July 9, 1917. Serial No. 179,464.

To all whom it may concern:

Be it known that I, MORGAN L. FITCH, a citizen of the United States, residing at Cooledge, in the county of Limestone and State of Texas, have invented new and useful Improvements in Stovepipe-Anchors for Tents, of which the following is a specification.

The present invention is a stove pipe anchor for use on tents and other portable structures, usually of fabric. I have found that where the stove pipe passes through a side wall or a roof wall in a tent structure, not only does the hole permit entrance of the elements but for some reason it impairs the draft. It is of course difficult to project the stove pipe directly through the apex of the roof, because of the existence of the ridge pole at that point, and yet such seems to be the logical outlet.

The purpose of the present invention is to provide the device somewhat in the nature of a ceiling plate or stove pipe nipple, and which serves as an anchor for the pipe and permits the latter to pass directly out through the ridge pole, at the center of its length or near either end of the tent. Incidentally, another purpose of the present invention is to exclude the elements as far as possible and to pierce the fabric of the tent roof and the rain-proof or ridge with very few holes or openings. Finally, the structure is adaptable to tents of different sizes and shapes, and may be detached or permitted to remain as a part of the ridge pole when the tent is taken down for storage or for transportation.

Details will be found in the following specification, reference being made to the accompanying drawings wherein:—

Figure 1 is a perspective view of one end of an ordinary A-tent, showing this structure as projecting through the top of the same.

Fig. 2 is an enlarged side elevation of the structure with the canvas omitted entirely.

Fig. 3 is a transverse sectional view through the center of the structure, with the canvas in place.

In the various views I have employed the reference letter P to designate the ridge pole, R is the canvas roof which overlies said pole, and S is the rain-proof or ridge which in fabric structures will be a comparatively narrow sheet of canvas extending along the apex of the roof and overly

ing the ridge pole on its exterior so as to thoroughly exclude the elements, even though the two sides of the roof be of separate sheets of fabric overlapping each other 60 along the pole, or perhaps merely led up to it and fastened upon it. Further details of the structure of the tent need not be described in this specification.

The numeral 1 designates a stove pipe 65 which in the present case we may assume rises vertically from a central draft camp stove and is of the proper material, diameter, and height to provide a good draft for such stove if the draft is not impaired by 70 extraneous conditions. On the assumption that the best draft is produced by passing this stove pipe directly through the apex of the roof, I first saw the pole P at the point where the pipe is to project, and remove a 75 piece therefrom so that the ends 2 and 3 of the parts or sections remaining are spaced from each other from four to six inches. Two metallic braces 4 are then provided, 80 each of strap iron of appropriate length and size, and each having end arms about eighteen inches long and an interposed bend or arch 5. The two arches are complementary of each other and stand opposite the space between the ends 2 and 3, whereas the arms 85 of the braces are laid alongside opposite faces of the pole P near where it is broken, and are firmly connected therewith by through bolts 6. The size of these elements should be such that the ridge pole as a 90 whole, after having been sawed apart and then spliced by these braces, is as strong as before. Directly above the opening between the two arches is a strap metal collar 7, and at least a foot above this collar is another 95 numbered 8. Both of these collars may have slots 9 and bolts 10 at their lapping ends, whereby their size can be adjusted to fit them closely around the stove pipe 1. Upright straps 11 and 12 are secured at their 100 upper ends to the sides of the upper collar, preferably crossing each other between their ends, and are secured near their lower ends at 13 to the lower collar 7, below which points they are bent outward as seen at 14 into fingers, for a purpose yet to appear.

The collars and the straps might well be of galvanized metal so as to prevent rust. Braces or guys in the shape of rods 15 have their upper ends forked as at 16 and then 110 secured as by rivets 17 to the upper collar, and their lower ends are passed downward,

- through holes 18 in the ridge pole and receive nuts 19 below these holes. As will be seen in the drawings, such holes will be bored obliquely through the parts of the ridge pole, and therefore when the nuts 19 are tightened up the guys are drawn downward and their forked upper ends are given a tendency to spread apart—thus holding the upper collar rigidly in place and under some tension. These guys also may be of galvanized metal to prevent rust. I have given approximate proportions and dimensions, but would not be limited in this respect.
- 15 In the application of this structure to a tent, after the ridge pole P is sawed and the braces applied as first explained above, the roof is laid over the same and an opening cut in it directly above the opening between the two arches 5. It may be well to bore the holes 18 subsequently through the roof and through the pole. The ridge sheet S is then applied and provided with an opening and holes, or if desired this may be applied over the roof and the holes formed in both pieces of fabric simultaneously. The guys are now inserted and the nuts applied from the interior, or if preferred the guys may be riveted to the upper collar first, and the exposed portion of the structure seen in Fig. 1 brought into place after the openings have been provided in the fabric sheets, so that when the lower ends of the guys are inserted the fingers of the straps assume their proper position. Their function is to overlie the ridge and hold it from being dislodged by winds, etc., and for this purpose they may be bent down onto the ridge S quite closely over the parts assembled. The pipe is now passed up through the openings in the various parts of the tent, and through both collars, after which the latter are set up tight by their adjusting means. Finally the operator goes inside the tent and tightens up on the nuts 19.
- Now when a fire is built in the stove, it will be found that the draft is as good as possible consistent with the locality in which the tent is located, and the surrounding objects such as trees and the like. Also it will be found that the elements can not enter the tent—at least, to any great extent. Even this may be avoided by telescoping the outside section of stovepipe onto the usual flange which forms a part of the rain-proof and the inside section of said stove-pipe into such flange; or a metal collar of flashing F might be employed around the stovepipe as indicated in dotted lines in Fig. 1, and if it fits the pipe close enough it will shed onto the roof whatever water runs down the pipe. The holes through which the guys pass will admit almost no moisture whatever. These guys brace the

skeleton structure which holds the exposed end of the pipe, even though it rise to a considerable height above the ridge pole.

What is claimed as new is:—

1. In a tent structure having an A-roof, 70 the combination with the ridge pole divided into sections separated at their contiguous ends, rigid braces having arms at their extremities lying alongside said sections and arches at their midlength standing opposite the space between the contiguous ends, and means for fastening the arms to the sections; of guys rising rigidly from the sections of the ridge pole and forked at their upper ends, and a collar supported 80 by such forked ends above the opening between said arches.
2. In a tent structure having an A-roof, 85 the combination with the ridge pole divided into sections separated at their contiguous ends, rigid braces having arms at their extremities lying alongside said sections and arches at their midlength standing opposite the space between the contiguous 90 ends, and means for fastening the arms to the sections; of a plurality of collars above the opening between said arches and in line therewith, means for connecting said collars, and pair of guy-rods connected at their upper ends with one of said 95 collars and having their lower ends passing through the sections of the ridge pole and receiving nuts.
3. In a tent structure having an A-roof, 100 the combination with the ridge pole divided into sections separated at their contiguous ends, rigid braces having arms at their extremities lying alongside said sections and arches at their midlength standing opposite the space between the contiguous ends, and means for fastening the arms to the section; 105 of a collar above the opening between said arches, a second collar above the first collar, stiff straps connecting said collars, means for adjusting the collars to the size 110 of the stove pipe, and guys leading from the uppermost collar downward to and connected with the sections of the ridge pole.
4. In a stove pipe anchor for tents and the like, the combination with a ridge pole 115 divided into sections whose contiguous ends are separated, rigid braces connecting said sections and having arches opposite the space between their ends, and the tent roof and ridge overlying the ridge pole and 120 braces and having registering openings above that between said arches; of upper and lower stove-pipe collars above the ridge and aligned with said openings, means for connecting them, and means for rigidly supporting one of said collars from the ridge pole.
5. In a stove pipe anchor for tents and the like, the combination with a ridge pole 125 divided into sections whose contiguous ends 130

are separated, rigid braces connecting said sections and having arches opposite the space between their ends, and the tent roof and ridge overlying the ridge pole and 5 braces and having registering openings above that between said arches; of upper and lower stove-pipe collars above the ridge and alined with said openings, stiff straps connected at their upper ends with the up-

per collar and near their lower ends with 10 the lower collar and having fingers closely overlying said ridge, guy-rods connected at their upper ends with the upper collar and having their lower portions passed through oblique holes in the sections of the pole, and 15 nuts on the lower ends of said rods.

In testimony whereof I affix my signature.
MORGAN L. FITCH.
